FURNACE DOORFRAME

Lawrence R. McAfoos, Pittsburgh, Pa., assignor
to Reliance Steel Products Company, Rankin,
Pa., a corporation of Pennsylvania

Application October 15, 1937, Serial No. 169,118

9 Claims. (Cl. 122—499)

My invention relates in general to furnace door frames and more particularly to water-cooled furnace door frames of the character employed in open hearth furnaces and the like.

The present invention represents an improvement over the invention shown and described in my United States Letters Patent No. 1,935,853, issued November 21, 1933. In the structure illustrated in that patent, there is a skeleton frame having two open spaces B above the furnace door opening A, two fluid inlets and one fluid outlet. In some installations it is preferred to cool the whole structure, and the door frame shown in my said patent is not as suitable for some installations as the present invention herein described.

In the accompanying drawing, which illustrates the present preferred embodiment of my invention:

Figure 1 is a front elevation of the frame;
Figure 2 is a vertical section on the line II—II of Figure 1, looking in the direction of arrows; and

Figure 3 is a horizontal section on the line III—III of Figure 1, looking in the direction of the arrows.

In the drawing there is shown a water-cooled door frame which has a body portion 3 forming the top of the frame, and side members or legs 4 and 5 extending along the sides of the body portion 3 and downwardly therefrom to the bottom of the furnace door opening A. Each of the legs 4 and 5 has projecting therefrom and at right angles thereto wing plates 7 and 8, respectively. These wing plates bear against the furnace walls (not shown) when the door frame is in position in the furnace structure.

The side or leg members 4 and 5 are preferably formed from sheet metal bent as shown in Figure 3 and welded at 9 to form an enclosed water passage. Each of the legs has a re-entrant portion 10 to provide guide means for a door 11, a part of which is shown in dotted lines in Figure 3. I prefer to form the wing plates 7 and 8 integral with the outside edge of the leg, although the wing plate may be separately formed and attached. Secured to the lower portion of leg member 4 is a U-shaped or channel member or conduit 12 which extends up along the leg 4 as shown, across the lower portion of body portion 3 forming a lintel 13 and thence downwardly along the other leg 5. The sides of conduit 12 are secured to the legs 4 and 5 as by welding to form a water-tight joint. The lower ends of legs 4 and 5 and associated conduit 12 are closed by plates 14 and 15, welded or otherwise secured in position. Washout plugs 16 and 17 are located adjacent the lower ends of the legs 4 and 5, respectively. Between the lower ends of leg 4 and member 12 an opening 18 is provided; likewise

an opening 19 is provided between the lower ends of the leg 5 and member 12.

A plate 20 is provided to cover the lintel portion of the conduit 12. This plate extends from a point adjacent the side of leg 4 and terminates in an upturned portion just short of the center line of the structure. A similar plate 21 extends from just beyond the center line to a point adjacent the leg 5. This construction provides openings 22, 23 and 24 leading from the conduit 12 into the enclosed body portion 3. If desired, openings may be formed in plates 20 and 21 at suitable intervals.

The body portion is enclosed by plates 25 and 26, welded to the legs 4 and 5 and to the conduit 12. The upper portions of the leg members and body portion 3 are closed by a plate 27. An inlet pipe 28 is provided through plate 27 into a chamber 29 formed in the upper part of leg 4 by plate 30. The plate 30 has an opening 31 leading into the leg member. Similarly the outlet pipe 32 passes through the plate 27 and into chamber 33 formed in the top of leg 5 by the plate 34. Plate 34 has a small hole 35 therein to permit the escape of any vapors or steam which may collect in leg 5 but it is not sufficient in size to allow any substantial amount of water to pass through. The chamber 33 is connected to the hollow body portion 3 by means of an opening 36 in the side wall of the leg 5. Leading from inlet chamber 29 is a pipe 37 which extends diagonally and downwardly through body portion 3 and is connected at 38 to leg 5.

As indicated by the arrows in Figure 1, the water circulation is as follows. Water or other cooling medium is introduced through inlet pipe 28 into chamber 29 from whence some of the fluid passes downwardly through leg 4 through opening 18 and up conduit 12 through passages 22 and 23 and into body portion 3. The rest of the water from chamber 29 passes through pipe 37 into leg 5 and from thence through passages 19 and conduit 12, through the passages 24 and 23 into the body portion 3. A comparatively small amount passes through opening 35 into outlet chamber 33. The water from the body portion 3 finally passes through opening 36 into chamber 33 and is discharged through the outlet 32.

It is apparent that I have provided a structure which is relatively inexpensive to construct and one which may be expeditiously and economically repaired, should the occasion arise. The amount of welding in the structure, of the character I have shown, is reduced to a minimum and there is a positive water circulation throughout all the structure and no dead pockets can form in which scale and dirt will be lodged, the presence of which would result in rapid deterioration of adjacent parts.

While I have illustrated and described the 60

present preferred embodiment of my invention, it is to be understood that it is not limited to the construction which I have shown and described, but it may be otherwise embodied within the scope of the following claims.

I claim:

5. 1. A hollow water-cooled furnace door frame comprising a hollow body portion at the top of the frame, two hollow legs forming the sides of the frame, a conduit extending along part of the 10 legs and between them to form the bottom of the body portion, an opening from each of said legs to said conduit adjacent the lowermost ends of the legs, an opening from said conduit to the body portion at the latter's lowermost portions, an 15 opening from the conduit to the body portion adjacent the lower center portion of the body portion, a fluid inlet connected to one leg and a fluid outlet connected to the body portion.
  20. 2. A hollow water-cooled furnace door frame comprising a hollow body portion at the top of the frame, two hollow legs forming the sides of the frame, a pipe connecting the legs through the body portion, a conduit extending along part of the 25 legs and between them to form the bottom of the body portion, an opening from each of said legs to said conduit adjacent the lowermost ends of the legs, an opening from said conduit to the body portion at the latter's lowermost portions, an 30 opening from the conduit to the body portion adjacent the lower center portion of the body portion, a fluid inlet connected to one leg and a fluid outlet connected to the body portion.
  35. 3. A hollow water-cooled furnace door frame comprising a hollow body portion at the top of the frame, two hollow legs forming the sides of the frame, a perforate plate near the upper part of one leg and extending across it to form a chamber, a fluid inlet pipe connected to the chamber, a pipe extending from the chamber to the other leg, a conduit extending along part of the legs and 40 between them to form the bottom of the body portion, an opening from each of said legs to said conduit adjacent the lowermost ends of the legs, an 45 opening from said conduit to the body portion at the latter's lowermost portions, an opening from the conduit to the body portion adjacent the lower center portion of the body portion, and a fluid outlet connected to the body portion.
  50. 4. A hollow water-cooled furnace door frame comprising a hollow body portion at the top of the frame, two hollow legs forming the sides of the frame, a perforate plate near the upper part of one leg and extending across it to form a chamber, a fluid inlet pipe connected to the chamber, a pipe extending from the chamber to the other leg, a conduit extending along part of the legs and 55 between them to form the bottom of the body portion, an opening from each of said legs to said conduit adjacent the lowermost ends of the legs, an 60 opening from said conduit to the body portion at the latter's lowermost portions, an opening from the conduit to the body portion adjacent the lower center portion of the body portion, and a discharge outlet connected to the upper end of the body portion.
  65. 5. A hollow water-cooled furnace door frame comprising a hollow body portion at the top of the frame, two hollow legs forming the sides of the frame, a pipe connecting the legs through the body portion, a conduit extending along part of the 70 legs and between them to form the bottom of the body portion, an opening from each of said
- legs to said conduit adjacent the lowermost ends of the legs, an opening from said conduit to the body portion at the latter's lowermost portions, an opening from the conduit to the body portion adjacent the lower center portion of the body portion, an outlet chamber in the top of one leg and separated therefrom by a plate, an opening from the body portion to the outlet chamber and a fluid outlet passage connected to the outlet chamber.
6. A hollow water-cooled furnace door frame comprising a hollow body portion at the top of the frame, two hollow legs forming the sides of the frame, a pipe connecting the legs through the body portion, a conduit extending along part of the 15 legs and between them to form the bottom of the body portion, an opening from each of said legs to said conduit adjacent the lowermost ends of the legs, an opening from said conduit to the body portion at the latter's lowermost portions, an opening from the conduit to the body portion adjacent the lower center portion of the body portion, an outlet chamber in the top of one leg and separated therefrom by a plate, a vent in the plate, an opening from the body portion to the 20 outlet chamber and a fluid outlet passage connected to the outlet chamber.
7. A hollow water-cooled furnace door frame comprising a hollow body portion at the top of the frame, two hollow legs forming the sides of the frame, a U-shaped open sided conduit extending along the lower part of each leg and secured thereto in such a manner that one side of the leg closes the open side of the conduit adjacent thereto, said conduit extending across the lower part of the body portion to form a lintel, a plate closing the open side of the conduit between the legs, said plate having openings therein extending from the conduit to the body portion, an opening from the bottom of each of said legs to said conduit, a fluid inlet connected to one leg and a fluid outlet connected to the body portion.
8. In a water cooled furnace door frame, spaced apart hollow legs extending from the top to the bottom of the frame, a conduit extending along part of the legs and between them to form a lintel, an opening from each of said legs to said conduit adjacent the lowermost ends of the legs, a hollow body portion between said legs and extending from the top of the frame to the lintel, said conduit having openings from the lintel portion extending to the hollow body portion, a fluid inlet at the top of one of said legs and a fluid outlet connected to the hollow body portion adjacent the top of the other leg.
9. In a water cooled furnace door frame, spaced apart hollow legs extending from the top to the bottom of the frame, a conduit extending along part of the legs and between them to form a lintel, an opening from each of said legs to said conduit adjacent the lowermost ends of the legs, a hollow body portion between said legs and extending from the top of the frame to the lintel, said conduit having openings from the lintel portion extending to the hollow body portion, a pipe connecting the legs and extending through the body portion, a fluid inlet connected to the top of one leg and an outlet chamber in the top of the other leg, said chamber being connected to the top portion of the hollow body portion and to a fluid outlet.

LAWRENCE R. McAFOOS.
